United States Patent Office.

PARDON H. GRISWOLD, OF GRAND RAPIDS, MICHIGAN.

Letters Patent No. 105,565, dated July 19, 1870.

IMPROVEMENT IN BARRELS.

The Schedule referred to in these Letters Patent and making part of the same.

To all whom it may concern:

Be it known that I, PARDON H. GRISWOLD, of Grand Rapids, in the county of Kent and State of Michigan, have invented certain new and useful Improvements in Barrels; and do hereby declare that the following is a full, clear, and exact description thereof, reference being had to the accompanying drawing and to the letters of reference marked thereon, making a part of this specification.

The nature of my invention consists in the construction and arrangement of a barrel, as will be hereinafter fully set forth.

In order to enable others skilled in the art to which my invention appertains to make and use the same, I will now proceed to describe its construction and operation, referring to the annexed drawing, in which—

Figure 1 is a side view;

Figure 2 is a vertical section; and

Figure 3 is a horizontal section of my improved barrel.

A A represent three sections of a barrel, in ring form, joined together by means of hoops B B on their outside, covering the joints.

There are also similar hoops B at the ends of the barrel.

The inside of the barrel thus formed is lined with staves C C, of suitable width and thickness. I pro-

pose making these staves of such width that five of them will line the entire inside of the barrel; but I do not confine myself to any particular number, as that may, of course, be varied to suit circumstances.

The staves C do not extend clear out to the ends of the barrel, but are somewhat shorter, so as to form a ledge near each end, on which the head D is to rest, said head being then secured by a wooden hoop, E, in the usual manner.

The grain of the wood in the lining C running at right angles with that of the sections A A makes the completed barrel very strong and tight.

The lining C is fastened by nails or any other suitable means.

Having thus fully described my invention,

What I claim as new, and desire to secure by Letters Patent, is—

The inside lining C, constructed as described and used within the sectional barrel A. B, substantially as shown and for the purposes herein set forth.

In testimony that I claim the foregoing, I have hereunto set my hand this 6th day of July, 1870.

PARDON H. GRISWOLD.
